[57] CLAIM

The ornamental design for a door closer bracket, as
shown.

DESCRIPTION

FIG. 1 is a front perspective view of a door closer
bracket embodying my new design;

FIG. 2 is a bottom plan view thereof;

FIG. 3 is a front elevational view thereof;

FIG. 4 is a rear elevational view thereof;

FIG. 5 is a left side elevational view thereof;

FIG. 6 is a front perspective view thereof in an alternate
position; and

FIG. 7 is a rear perspective view thereof in another
alternate position.
